US00D867036S

(12) **United States Design Patent** (10) **Patent No.:** **US D867,036 S**
(45) **Date of Patent:** **** Nov. 19, 2019**

(54) **RETAIL FIXTURE**

- (71) Applicant: **Apple Inc.**, Cupertino, CA (US)
- (72) Inventors: **Alice Marlin Brugger**, San Francisco, CA (US); **Manuel DeJesus**, San Francisco, CA (US); **Joshua Robert Edwards**, Santa Cruz, CA (US); **Jean-Marc Gady**, Los Altos, CA (US); **Wesley Bryan Hamm**, San Francisco, CA (US); **Russell John Kaaihue Heirakuji**, Cupertino, CA (US); **Allison Inouye**, San Francisco, CA (US); **Moritz Wilsberg**, Menlo Park, CA (US)
- (73) Assignee: **Apple Inc.**, Cupertino, CA (US)
- (**) Term: **15 Years**
- (21) Appl. No.: **29/681,844**
- (22) Filed: **Feb. 28, 2019**

Related U.S. Application Data

- (63) Continuation of application No. 29/655,973, filed on Jul. 9, 2018.
- (51) **LOC (12) Cl.** **06-06**
- (52) **U.S. Cl.** **USPC** **D6/675**

Primary Examiner — Kelley A Donnelly

(74) *Attorney, Agent, or Firm* — Sterne, Kessler, Goldstein & Fox P.L.L.C.

(57) **CLAIM**

The ornamental design for a retail fixture, as shown and described.

DESCRIPTION

FIG. 1 is a top front perspective view of a retail fixture showing the claimed design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a top front perspective view of another retail fixture showing the claimed design;
FIG. 9 is a front view thereof;
FIG. 10 is a rear view thereof;
FIG. 11 is a left side view thereof;
FIG. 12 is a right side view thereof;
FIG. 13 is a top view thereof; and,
FIG. 14 is a bottom view thereof.

The broken lines in the figures show portions of the retail fixture that form no part of the claimed design.

1 Claim, 10 Drawing Sheets
